UNITED STATES PATENT OFFICE.

CHARLES D. LANNING, OF DORCHESTER, MASSACHUSETTS.

WARP-LEASING MACHINE.

1,145,322.

Specification of Letters Patent.

Patented July 6, 1915.

Application filed March 19, 1906. Serial No. 306,699.

To all whom it may concern:

Be it known that I, CHARLES D. LANNING, a citizen of the United States, residing at Dorchester, in the county of Suffolk and State of Massachusetts, have invented an Improvement in Warp-Leasing Machines, of which the following description, in connection with the accompanying drawings, is a specification, like letters on the drawings representing like parts.

My invention relates particularly to warp leasing machines intended for mechanically leasing a warp, and particularly a new warp, which it is desired to have leased prior to its insertion in the loom.

My invention will be best understood by reference to the following specification, when taken in connection with the accompanying illustration of one specific embodiment thereof, while its scope will be more particularly pointed out in the appended claims.

In the drawings,—Figure 1 is an elevation, partly broken away, showing a machine embodying one form of my invention; Fig. 2 shows the same machine in end elevation; Fig. 3 is a fragmentary view, with various parts removed to show the relation of the needle to the lease rods and the warp when seizing a thread thereof; Fig. 4 is a similar but more elaborated view showing the needle in its retracted position; Fig. 5 is a view similar to Fig. 3 showing the advanced needle but the reversed or shifted relation of the lease rod; Fig. 6, is a side elevation on an enlarged scale of the warp-feeding ratchet and pawl device, and Fig. 7, is an end elevation of the same.

While the various elements of the machine to be described may be arranged in other relations than those set forth, and while the details thereof may be widely varied from those disclosed in the herein specific and illustrative form of machine, there is here provided a carriage sustaining a reciprocatory warp drawing needle and operating mechanism therefor, which carriage is caused to advance progressively lengthwise the machine to traverse the warp, the latter being maintained with its threads under tension and arranged in substantially parallel alinement. The advancing needle is caused to seize the foremost warp thread and to draw the same between suitably positioned lease members, there being provided to coöperate with the needle suitable stripping mechanism for stripping the drawn

thread from the needle and also means for thrusting aside the leased threads from the line of needle action. At suitable times, and herein between each successive thread drawing, the relation of the lease members is shifted by suitable pattern means, so that in the described machine the successive threads are reversely arranged between the lease members. In the described machine there is also provided mechanism for selecting and separating the foremost threads of the warp in preparation for the drawing operation and compensating feeding devices permitting the adjustment of the warp to correct for irregularities in the spacing of the warp threads or for spacing which departs from the periodic advance of the drawing mechanism.

Referring to the drawings, and to the illustrative embodiment of my invention there is provided a bed or frame a , suitably supported by the legs a' and carrying the overhead structure or arched frame a^2 which serves as a support for the warp carriage, lease members and other mechanism.

The warp is sustained during the operation of the machine in a warp carriage or holder of any suitable construction but which here comprises the end frame members b , which are connected by a pair of rods b' , and have each the upper and lower clamping jaws b^2 and b^3 respectively. The carriage is supported upon the frame by a pair of oppositely extended hanger rods b^4 , resting on roller supports b^6 and thereby sustaining the carriage for longitudinal adjustment lengthwise the machine. The frame members are also provided with oppositely extended lower supporting rods b^5 which the weight of the carriage causes to press against vertically disposed rollers b^7 on the stationary frame of the machine.

The warp when positioned in the machine has its free ends clamped by the usual clamp bar c (Figs. 3-5) which is placed in the upper pair of clamping jaws b^2 . When in that position the previously withdrawn separator shaft d (Fig. 4) is replaced in the machine and the threads are clamped by a second clamp bar c' placed in the lower pair of clamping jaws b^3 , so that the warp assumes the position shown in Figs. 2-5 of the drawings. The lower clamping jaws are mounted upon slides b^8 , which have rack and pinion connections with the rod b^8 and its operating handle b^9 , so that when in the position

described the clamping bar c' may be adjusted up or down to place the necessary tension upon the warp threads over the separator shaft.

5 The drawing needle e is mounted upon the carriage E , which latter is adapted to slide lengthwise the machine and transversely the warp upon suitable ways formed in the bed plate a of the machine, the needle during 10 advance of the carriage undergoing reciprocatory movement to and from the threads of the warp. For advance of the carriage the latter is provided with the split nut e' , (Fig. 4) which may be thrown into or out 15 of engagement with the lead screw f by means of the hand lever e'' .

The lead screw is continuously rotated during the operation of the machine for the gradual advance of the carriage by means of 20 the gear f' (Fig. 2) carried at its end, said gear being driven through the intermediate gears f^2, f^3 by the pinion f^4 upon the end of the main drive shaft g . The intermediate gears f^2, f^3 are journaled on an arm 25 f^5 carried by the drive shaft g , which arm may be swung to any desired position and there clamped upon the clamping segment f^6 permitting the substitution of gears of different sizes to change the speed of rotation of the lead screw when desired. The 30 drive shaft carries at its opposite end (Fig. 1) the loosely journaled driving pulley g' , which may be clutched to the shaft by means of the sliding clutch member g^2 , the latter in turn being operated by the lever 35 g^3 , link g^4 , upright lever g^5 and horizontal sliding actuating rod g^6 , the latter extending the full length of the machine so that the main drive shaft clutch may be thrown in 40 or out of engagement by the operator at any point along the machine.

The drive shaft is splined to permit driving engagement therewith of the gear g^7 , (Fig. 4) the latter mounted to slide with 45 the carriage lengthwise the machine and acting to drive the operating mechanism thereon. The gear g^7 engages the needle operating gear e^8 , which latter acts through an intermediate gear and crank disk e^9 to move 50 the pivoted arm e^4 and the link e^5 for reciprocation of the drawing needle e , which latter slides in a sleeve or cylinder e^6 and is given a partial turn on its advance and retraction by the engagement of a pin upon 55 the needle with a partially spiraled slot in the sleeve. The movement of the needle is so timed that it undergoes one complete reciprocation as the carriage is advanced a space corresponding approximately to the 60 spacing between successive warp threads.

Acting in advance of the needle, and herein in progressively advancing with the carriage, there is provided thread-separating means for selecting and separating the 65 most warp threads. In the described em-

bodiment of my invention this consists of a sleeve d' slidable upon the separating shaft d , but keyed thereto to be turned thereby. This sleeve is provided with a grooved collar d^2 engaged by a yoke d^3 carried by a 70 standard d^4 upon the carriage, so that with the advance of the carriage the sleeve also is caused to advance lengthwise the shaft. The advanced end of the sleeve is provided with a tapered end having corrugations d^5 , 75 which as they pass beneath the warp threads tend to stroke the latter into parallelism and place increased tension thereon. Further advance thereof forces the threads upon the threaded portion d^6 of the sleeve, where the 80 foremost thread is engaged by the advancing lip of the screw, successive threads being separated in accordance with the pitch of the screw and advanced one by one within the line of needle action. To maintain the 85 threads in certain engagement with the separating screw there is provided the overlying tension finger d^7 , carried by the swinging arm d^8 , supported upon the standard d^4 and pressed against the threads engaged by 90 the screw through the medium of the torsion spring d^9 . Continuous and suitable rotative movement is imparted to the separator shaft d and therethrough to the separating screw by the bevel gear d^{10} carried at 95 the end of the shaft, and engaging the corresponding bevel pinion d^{11} upon the inclined shaft d^{12} , the latter being driven from the bevel gear d^{13} upon the main driving shaft g .

The threads when engaged by the needle are drawn between suitably positioned lease members. These may be of any desired number and arranged for any desired movement, but in the described machine they consist of a pair of lease rods h, h' (Fig. 4) and the separately movable lease rod i . The rods h, h' on the one hand and the rod i on the other are held parallel with the travel of the needle but capable of vertical and opposite reciprocatory movement above and below the plane of needle action. For this purpose there are provided at opposite ends of the machine, vertically slidable in suitable guideways in the frame, pattern frames h^2 supporting the rods h, h' and pattern frames i' supporting the rod i . These frames are given reciprocatory movement through pins h^3 and i^2 secured respectively 110 to the frames h^2 and i' and engaging with suitably formed slots in the pattern disks k , the latter given a reciprocatory movement by the rocking shaft k' , which extends lengthwise the machine. This shaft is oscillated by the crank arm k^2 connected at 115 one end thereto, and its attached link k^3 connected to the overhead crank disk k^4 , the latter being driven by a gear k^5 in engagement with the pinion k^6 upon the separator shaft d .

By reason of the uniform and continuous reciprocatory movement which is given the pattern disk k , the lease rods are caused to reciprocate vertically between successive 5 thread drawings, so that while positioned as shown in Fig. 3 prior to the drawing of one thread, they are subsequently reversed and positioned as shown in Fig. 5 prior to the drawing of the next succeeding thread. 10 They are then again returned to the position shown in Fig. 3, and so on, this resulting in the positioning of successively drawn threads on opposite sides of the lease rods.

In the described machine, the thread as it 15 is drawn between the lease rods, is also drawn into engagement with suitable means which tend to retain it in approximately its drawn position and prevent the entanglement or displacement of the leased thread. 20 In the described machine this is obtained by providing a series of closely arranged members, such as the resilient bristles l , or the like, the lower ends of which are held fast in the supporting bar l' , the latter however, 25 being so positioned as to present the line of bristles transverse to the line of needle action. This results in causing the free ends of the threads to be drawn and laid in the bristles, where they are held with sufficient 30 certainty to prevent displacement of the leased warp. The bristle-holding support l' is sustained by the depending hangers l^2 supported on the overhead frame a^2 .

The free end of the thread after being 35 withdrawn between the lease rods and through the bristles is stripped from the needle by the reciprocatory knock-off finger m , which on full retraction of the needle is caused to move transversely across the 40 needle path and strip the free thread end from the needle hook, returning, however, to its normal position before the next advance of the needle. The stripper m is pivoted upon the frame at m' and is given reciprocatory movement like that of a connecting rod through its connection to the crank disk m^2 , the latter being driven by the bevel gearing m^3 from the carriage counter-shaft m^4 , the latter in turn being driven 50 from the needle operative crank disk e^x . The proportions of the gears are such that the stripper is caused to execute its stripping movement upon each retraction of the needle.

55 Upon the drawing of each thread between the lease rods the last thread drawn is pressed back against the remainder of the already leased warp to thrust aside the leased threads away from the line of needle action. This is accomplished by the forked displacing lever n (Figs. 3-5), the two bifurcations of which work between adjacent lease rods and are moved from one side of the line of needle action after the needle 60 retraction across the line of needle action to

displace the leased threads to one side. The displacing lever is pivoted at n' upon the carriage E to travel therewith, and is also connected to the crank disk m^2 by the link connection n^2 .

70 The crank disk being rotated by the bevel gearing referred to, and the distance between the center of the disk and its connection to the link n^2 being less than the distance between the lever pivot n' and its connection to the link, the displacing lever receives a suitable swinging reciprocatory movement from the rotation of the disk.

75 The advance of the drawing needle is proportioned by suitable selecting gears f^2 , f^3 80 with close approximation to the spacing of the warp threads. The threads of a warp, however, usually present localized irregularities which tend to cause the foremost warp thread to deviate more or less from the line of needle action. To suitably correct errors of this kind there is provided a hand adjustment accessible to the operator of the machine for adjusting the entire series of warp threads lengthwise the travel 85 of the needle and properly alining the foremost thread thereof with the axis of the needle. For this purpose the overhead end rod g^6 is suitably journaled for rotative movement in the frame, a^2 and is provided 90 at one end with the pulley o , which is connected by the depending band or belt o' with the underneath pulley o^2 , the latter journaled in the machine and secured to the worm o^3 , of large diameter. The latter is 95 caused to engage with suitably formed teeth in the side or face of the adjacent hanger rod b^5 upon the warp carriage, so that on movement of the worm the carriage is given a slight compensating movement lengthwise 100 of the machine.

105 For the purpose of operating the machine with reference to a series of warps of slightly varying width where it is undesirable or inconvenient repeatedly to change the gears f^2 , f^3 , with each new warp placed on the machine, or where variations in the warp widths may be too slight for compensation through a change of gears, it is desirable also to provide, either with, or in substitution for, the hand adjustment described, an automatic compensating feed 110 which shall correct for deviations in the average spacing of the warp threads from the assigned periodic advance of the drawing needle. With such automatic compensating feed the carriage driving gears are 115 adjusted to give a feed corresponding approximately to the spacing of the warp threads and the warp carriage in addition is also given a slight incremental step-by-step advance to correct for deviations of the carriage advance from the exact amount which is desired. For this purpose near the 120 end of the lead screw f (Fig. 2) there is 125 130

provided a cam p which engages at each rotation of the lead screw with a swinging arm p' , one end of which is pivoted to the frame and the opposite end adjustably secured to a connecting rod or link p^2 . The opposite end of the latter is secured to a swinging pawl lever p^3 , (see Figs. 6 and 7) fixedly secured to a pin p^4 , the pin carrying at its opposite end a pawl p^5 . The pin itself is journaled in an arm p^6 , the latter swingingly mounted upon the end of the shaft which carries the worm o^3 but provided with some friction device, such as the spring pressed washer p^8 so that there is provided a slight resistance to its swinging movement upon the said shaft. When the rod or link p^2 is advanced by engagement of the lead shaft cam with the arm p' , the pawl pin is turned to carry the pawl against the serrated edge of the ratchet wheel p^7 secured to the worm o^3 to give the latter a slight rotative movement, the arm p^6 being then held by the friction device referred to. The moment the pawl nose engages with the ratchet wheel the movement of the pawl is completed with the arm p^6 and the lever p^3 moving as a unit. When the lead shaft cam drops away from the lever arm p' , the latter is returned by the spring p^9 , moving the lever p^3 against the stop screw p^9 upon the lever arm p^6 , and causing the return of the parts to the position shown in Fig. 2. There is given therefore for each revolution of the lead screw shaft a slight shifting movement of the warp carrier, the movement of which can be varied by adjusting the stop screw p^9 or the connection between the rod p^2 and the swinging arm p' . The amount and direction of this shifting movement may be proportioned to maintain a correct alinement between the drawing needle and the foremost warp thread.

To assist the operator in moving the parts of the machine by hand for adjustment or other purpose, the lead screw end is provided with a crank handle r and the needle operating gear is also provided with a separate crank handle r' . The operator customarily stands at the side of the machine near the warp carriage and to enable him to move the needle by hand from that side of the machine, there is provided a pulley r^2 connected to the needle driving gear e^3 through the main shaft m^5 and gears m^6 and m^7 at one side and at the other side connected through the band or belt r^3 with the overhead pulley r^4 , which latter has the crank handle r^5 accessible to the operator on the opposite side of the machine.

While I have shown and described one form of my invention, it is to be understood that the same is not limited to the details herein shown, or the particular arrangement of operating parts, or the mode of sustaining the warp with reference to the operating

elements of the machine, but that extensive modifications in the illustrated details may be made and wide departures therefrom followed without deviating from the spirit of my invention.

I claim—

1. A warp-leasing machine having a frame, a warp holder supported for longitudinal adjustment lengthwise the frame and adapted to sustain the warp threads under tension in substantially parallel alinement upon said frame, mechanism for traversing lengthwise the frame and transversely the warp, a drawing needle, means for intermittently reciprocating the drawing needle during its traverse to engage and draw successive threads of the warp, a plurality of lease members between the drawing needle and the warp between which said threads are drawn, pattern frames sustaining said lease members, mechanism for intermittently reciprocating said pattern frames to shift the relation of said members between successive thread drawings, a series of bristles for retaining the free ends of the drawn threads, means for stripping the free thread ends from the drawing needle, a vibratory displacing member for displacing the leased threads from the line of action of the drawing needle, means for selecting and separating the foremost warp threads prior to action thereon by the drawing needle, and means permitting compensating feeding adjustment of the warp holder.

2. A warp-leasing machine having means for holding distended a series of warp threads, a drawing needle, a carriage therefor, means for causing the carriage to traverse the warp and also for giving the drawing needle intermittent reciprocatory movement to engage successive warp threads and draw the same, a plurality of lease members between the drawing needle and the warp, between which the threads are drawn, and means for shifting the relation of the lease members between successive actions of the drawing needle.

3. A warp-leasing machine having means for holding distended a series of warp threads, a plurality of lease members adjacent the same, means for progressively acting upon the warp threads and for drawing the same between the lease members, means for intermittently shifting the relation of the lease members, and means for compensatingly adjusting the position of the warp holder.

4. In a machine for acting upon warp threads, the combination with means for holding distended a series of warp threads, means for supporting a plurality of lease members adjacent thereto, means for acting upon successive warp threads, and means for intermittently shifting the relation of the lease members.

5. A warp-leasing machine having a plurality of lease members, means for successively drawing warp threads between said lease members, and means for shifting the relation of the lease members. 10
6. In a machine for acting upon warp threads the combination with means for supporting a warp in unleased condition, of a thread placing device and leasing means coöoperating therewith for placing the warp in a leased condition. 15
7. In a machine for acting upon warp threads, the combination with means for supporting a warp in unleased condition of leasing members and a drawing-in device for drawing the warp into a leased condition. 20
8. A machine for acting upon warp threads having means for supporting the warp in unleased condition, means acting progressively to draw the warp into a leased condition, and compensating feeding means permitting the adjustment of the foremost warp thread with reference to the line of action. 25
9. A machine for acting upon warp threads having means for supporting the warp in unleased condition, means for drawing the warp into a leased condition, and compensating feeding means for the warp support. 30
10. A machine for acting upon warp threads having means for supporting the warp in unleased condition, means for drawing the warp into a leased condition, and automatic compensating feeding means for the warp support. 35
11. A machine for acting upon warp threads having means for supporting the warp in unleased condition, means for drawing the warp into a leased condition, and hand compensating feeding means for the warp support. 40
12. A machine for drawing warp threads having means for supporting the warp in unleased condition, thread-drawing means and a series of bristles within the path of the drawing-in means through which bristles the free ends of the threads are drawn. 45
13. A warp-drawing machine having means for supporting a warp, means for successively drawing the threads therefrom, and a series of closely arranged resilient members having free ends and arranged in the line of drawing action to retain the free ends of the drawn threads. 50
14. A warp-leasing machine having means for supporting a warp in unleased condition, means for drawing the warp threads into a leased condition, and a series of closely arranged resilient members in the line of drawing action for retaining the free ends of the drawn threads. 55
15. A warp-leasing machine having means for supporting a warp in unleased condition, means for drawing the threads of the warp into a leased condition, and means for displacing the drawn threads from the line of drawing action. 60
16. A warp drawing machine having a drawing needle, means for supporting a warp in unleased condition, means for drawing the threads thereof into leased relation, and means for stripping the drawn threads from the drawing needle. 65
17. A warp-leasing machine having lease members, means for drawing the thread between the lease members, and means acting between adjacent lease members to displace the leased threads from the line of drawing action. 70
18. A warp-leasing machine having a plurality of lease members, means for holding a series of warp threads, means for selecting and separating the foremost threads thereof, and means for placing said separated threads between said lease members in desired relation. 75
19. A warp leasing machine having the holder *b* for holding the warp, lease members *h* and *i*, means for moving the members relatively to the needle path and the needle *e* for drawing the threads between the lease members. 80
20. A machine for acting upon warp threads having means for supporting the warp in unleased condition, means for placing the warp in a leased condition and combined hand and automatic compensating feeding means for the warp support. 85
21. In a machine for acting upon warp threads preliminarily to the weaving operation, the combination with means for supporting a warp, and coöoperating instrumentalities for progressively engaging successive threads and placing the same each in a leased, non-woven condition relatively to the preceding one. 90
22. A machine for acting upon warp threads having a support for an unleased warp, a pair of lease members, means to engage successive threads to locate them in succession between the lease members and means to move the lease members to reverse the relation thereof to successive threads. 95
23. A machine for acting upon warp threads having a support for an unleased warp, a pair of lease members, means to cause relative movement between the lease members and successive threads, thereby to locate the latter in succession between the lease members and means to cause reversal of the relation of the lease members with respect to the threads, to form the lease. 100
24. In a machine for leasing warps the combination with means for holding the warp, of means adapted to hold the lease and means adapted to alternately reciprocate the said lease holding means above and beneath the plane of the warp, substantially as and for the purpose set forth. 105
- 110
- 115
- 120
- 125
- 130

25. In a machine for leasing warps the combination with the warp holding means, of lease holding means and means for imparting reciprocatory motion to said lease holding means after the leasing of each warp thread alternately from above to beneath the plane of the warp and from beneath to above the latter, substantially as and for the purpose set forth.
- 10 26. In a machine for leasing warps the combination with the warp holding means, of lease holding members and means for causing these lease holding members after each warp thread leased to reciprocate alternately from above to beneath the plane of the warp and from beneath to above the latter, substantially as and for the purpose set forth.
- 20 27. In a machine for leasing warps the combination with the means for holding the warp in a plane, of lease holding members, slides slidably mounted in a plane which is perpendicular to that of the warp and parallel to the warp threads and means for causing the said slides to move toward one another, substantially as and for the purpose set forth.
- 30 28. A machine for acting upon warp threads preliminarily to the weaving operation, having means for supporting an unleased warp, a pair of lease members, means operatively associated with said lease members and the warp threads to effect a relative movement between the lease members and the threads of the warp taken in succession from one side thereof to the other, thereby to place the threads in non-woven condition between said members, and means to cause reversal of the relation of the lease members 40 with respect to the threads, to form the lease.
- 35 29. A machine for acting upon warp threads having means for supporting an unleased warp, a pair of lease members, and means for placing the warp in a leased condition relatively to the lease members, said placing means including means acting progressively upon successive threads of the warp and also means to cause relative movement between the placing means and the lease members to effect successive leasing of the threads.
- 45 30. In a machine for acting upon warp threads preliminarily to the weaving operation, the combination with means for supporting a warp in unleased condition, of
- 50 mechanism coacting therewith and acting in succession upon the threads of the warp from one side thereof to the other, for automatically placing the warp in leased, non-woven condition.
- 55 31. A machine for automatically placing an unleased warp into leased formation, embodying, in combination with means to hold the unleased warp and a pair of lease-holding members, mechanism successively to engage, separate, and position the warp threads and acting progressively thereon from side to side of the warp, and devices to put the said lease-holding members into 60 reversed relation successively, transverse the warp, with the threads after being positioned by the said mechanism.
- 65 32. In a machine for acting upon warp threads preliminarily to the weaving operation, the combination with means for supporting a warp and coöperating instrumentalities acting in advance of the weaving operation, for progressively engaging successive threads and placing the same each in a 70 leased condition, relatively to the preceding one.
- 75 33. A machine for acting upon warp threads having a support for an unleased warp, a pair of lease members, and coöperating instrumentalities to cause relative movement between the lease members and successive threads, thereby to locate the latter in succession between the lease members and then to reverse the relation of successive 80 threads to the lease members to form the lease.
- 85 34. A machine for acting upon warp threads having a support for an unleased warp, a pair of lease members and coöperating means operatively connected with said lease members and having movement affecting relative change in position of said lease members and successive threads, and to reverse the relation of successive threads to 90 the lease members to form the lease and means having relative movement with respect to said leasing members to locate the threads in succession between the lease members.
- 95 In testimony whereof, I have signed my name to this specification, in the presence of two subscribing witnesses.

CHARLES D. LANNING.
